MULTICOLOR PLATE PRINTING TISSUES OR
OTHER MATTERS

Jean Baptiste Dufour, Villeurbanne, France

Application August 9, 1939, Serial No. 289,235
In France August 26, 1938

2 Claims. (Cl. 101—171)

It has still been proposed to apply multicolor plate printing processes in which the parts in relief securing the printing penetrate, for their inking, into individual compartments the profile of which corresponds with that of the design, and which are obtained either by welded separating partitions or by forming in a plate, made up of wood or other matter, a negative of the printing plate properly so called.

According to another known process, the parts in relief of the plate are brought into contact with the felts filling up these individual compartments.

In any case and whatever the used process may be, including also the usual process with only one color at once, the plate is applied in the same manner as a printing stamp or stereotype-plate. In other words, the lower surface of its parties in relief which must make up the design is impregnated with the color, and printing is effected by applying on the tissue or other matter this lower surface bearing the color.

My new plate printing process obviates the drawbacks of the known processes mentioned above and offers, moreover, numerous advantages, the essential of which are:

(1) To enable the simultaneous applying, at a lower expense, of a great number of colors.

(2) To enable the carrying out of a great number of designs by the aid of only one feeding apparatus, by changing only the plate absorbing by capillarity, in some tubes or others of the feeding apparatus, the colors corresponding with the design of the plate.

(3) To obviate any risk of spotting the tissue to be printed by detaching the small color drops preceding the application of the color on the tissue.

The new process essentially relates to the drawing up of the colors by the aid of one of the faces of the plate and to the obtention of the printing properly so called by the help of its other face by turning it upside down causing thus the color to be brought up to the printing surfaces.

According to the embodiment of the invention mentioned hereafter as being more particularly advantageous, the printing plate is made up of a printing plate properly so called connected with another plate bearing inking tubes, the printing plate properly so called supporting felts, flannels, cottons or flat wicks cut out or folded to correspond with the shape of the design and slightly fitted in, and which is provided with some perforations for the passage of the inking tubes, this printing plate being screwed on the said plate

supporting the inking tubes bored so as to correspond with the holes of the printing plate and bearing, screwed in its perforations, inking tubes provided with an inner packing, such as a fine rolled up brass wire-work, and having on their extremity a very fine welded sieve made up of wire-work, which, working in the same manner as the inner one, retains the color by capillarity when the plate is set on the feeding apparatus, and brings then the color up to the felts when the turned plate is applied on the tissue.

According to another equally very advantageous embodiment of the invention, the feeding apparatus consists of a certain number of superposed tanks on which are welded feeding tubes whose number may be variable, and which are arranged, by preference, vertically, forming a draught-board or a quincunx rising somewhat higher than the upper part of the apparatus, and in which immerge the inking tubes of the printing plate, when the latter is set on the feeding apparatus, the color being brought up to the said superposed tanks and feeding tubes by the aid of an equal number of side tanks connected with the first one by the help of brass or rubber tubes arranged side by side on the one side of the feeding apparatus, at such a height that, on the principle of communicating vessels, the color comes in the feeding tubes up to the level necessary to dip the inking tubes in the liquid.

The following is a complementary description enabling a better understanding of the invention as also drawings, it being understood that these are given only by way of illustration and can be varied widely without departing from the invention.

Fig. 1 is a perspective view of a printing plate according to the invention.

Fig. 2 is a sectional view.

Fig. 3 is an elevation view with partial section of the feeding apparatus.

Fig. 4 is a partial ground view.

In the embodiment given only by way of illustration, the printing plate is made up of a printing plate properly so called 22 constituted, by preference, of wood veneered on both sides and carefully varnished to avoid any deformation by humidity. The even surface of each design 23 to be reproduced is made up of a piece of felt, flannel or other tissue or spongy matter cut out to correspond with the shape of the design, and fixed, by preference, by means of pins 24 or by pasting, on the wood in which it is slightly incrusted, it being moreover slightly in relief with respect to the level of the plate. The separating parties for

the color may be varnished in order that the limits of the colors may be strictly fixed, but some junctions may also remain unvarnished giving thus an uniform aspect to the colors arranged side by side.

The plate 22 has some holes 25 whose number may vary and which are arranged at variable distances according to the feeding apparatus. These holes are intended for the passage of the inking tubes 26 which are supported by the metallic plate 27 made up, by preference, of aluminium, and on which is fixed, by the aid of the screws 28, the plate 22. On the plate 27 are cut screws to receive the inking tubes 26. These inking tubes 10 are provided with an inner packing consisting of a very fine rolled up brass wire-work 29 that may be substituted, if necessary, by a wick, flocks or cotton or other spongy matter. They bear on their lower extremity a very fine welded wire-work 15 sieve 30 intended, as it is also the case with the inner packing 29, to retain by capillarity the color. The upper part of the printing tubes 26 goes through the metallic plate 27 and penetrates into the holes 25 in such a manner as to cause the upper extremity of the tube to touch the under side of the felts. The length of the lower part of the inking tubes 26 is calculated so as to dip in the feeding tube of the feeding apparatus when the printing plate is put in it. 20

Handles 31 of an adequate shape are fixed on each side of the printing plate, so as not to hinder the application of the turned over plate on the tissue.

The feeding apparatus foreseen for the inking of printing plate comprises a number of superposed tanks 1 to 16 equal to the number of the various colors and tints that one wants to obtain on the printed tissue (sixteen in the example of this invention). Each of these tanks 35 1 to 16 is provided with a blow off cock 33 and is topped by a certain number of vertical feeding tubes 34 which cross the upper tanks through the flues 35 and end at the top of the feeding apparatus. These vertical tubes may be arranged to 40 form a draught-board on the surface of the tanks, but, if necessary, they may also be arranged to form a quincunx or in any other manner, so as to vary the space between them. Fig. 4 schematically points out this draught-board arrangement, the number written down in the inner part of each compartment corresponding with the number of the tank whose vertical tube is in the said compartment. This combination is more 45 particularly advantageous for color designs very close to each other and combined with the printing plate system mentioned above which enables the execution of a great number of designs with only one feeding apparatus because of the great closeness of the colors. Are to be changed 50 only the plate absorbing by capillarity, in all the tubes of the feeding apparatus. The colors corresponding with the design to be reproduced, and, on the other hand, the arrangement of the tubes.

In order to maintain the level of the liquid color in the feeding tubes 34 at a constant value, 55 each of the superposed tanks 1 to 16 is connected by the aid of a metallic or rubber pipe, with the tank 37 arranged on the side of the feeding apparatus. The juxtaposed tanks 37 are at the same 60 height as the upper extremity of the feeding tubes 34, and, on the principle of communicating

vessels, the level of the liquid is the same in the said tanks 36 and the feeding tubes 34. When the inking tubes are dipped in the feeding tubes, it is sure that they become well impregnated with the color.

In order to provoke the printing of a tissue with the aid of the printing plate by making use of the feeding apparatus mentioned above the printing plate is taken by the handles 31, the inking tubes 26 being then turned down. The 10 plate is applied on the feeding apparatus, so as to secure the penetration of each inking tube into a vertical feeding tube 34. Within some seconds the inking tubes will absorb by capillarity a sufficient quantity of the color, so that the color remaining in the tubes is quite sufficient for the inking of the felts. The printing plate will then be lifted up, and after having turned it, its felted face will be applied on the tissue to be printed. 15

The invention is in no wise limited to the embodiment mentioned above, but it encompasses, on the contrary, any other variation and more particularly the formation of the design of the printing plate by means of a felt covering the whole plate but whose hollow shapes will be 20 slightly deeper, and the partings coated with any fat varnish or glue insoluble in water or alcohol. A very elastic matter, such as rubber moss cut out and sufficiently in relief with respect to the felt 25 in order that it may be inked with gum, color, chemical discharge or other matter without touching the felt, may be incrusted in the wood and between the designs of the felt. When a slightly greater pressure is applied on the plate 30 lying on the tissue, the rubber moss prints along with the other colors which are also brought into contact with the tissue. This combination enables the obtention of a great many of new fashions.

What I claim and desire to secure by Letters 40 Patent is:

1. Multicolor printing device comprising in combination a printing plate, a plurality of printing pads of porous and elastic material mounted on and slightly projecting from one face of said plate, said printing pads being shaped and arranged in accordance with the multicolor pattern to be printed, a plurality of ink feed tubes, each of said ink feed tubes penetrating said printing plate rearwardly of one of said printing pads and projecting from the face of said plate opposite that on which said pads are mounted, an assembly of constant and uniform level ink wells, each ink well being adapted and arranged to freely receive the projecting end of an ink feed 50 tube when said printing plate is placed on said ink well assembly with the printing pads facing upwardly, and capillary active fillings in said ink feed tubes to absorb the ink rapidly from said ink wells when said printing plate has been 55 placed on said ink well assembly and to distribute said ink evenly and at a predetermined rate to the corresponding printing pads, respectively, when the printing plate is removed from the ink well assembly and turned upside down for the 60 execution of prints.

2. A device, as claimed in claim 1, in which said capillary active fillings of said ink feed tubes comprise rolls of fine brass wire work.

JEAN BAPTISTE DUFOUR.
